Letvin, Philadelphia, Pa.

Application September 24, 1942, Serial No. 459,509

8 Claims. (Cl. 122—491)

(Granted under the act of March 3, 1883, as
amended April 30, 1928; 370 O. G. 757)

Our invention relates to vapor generators and more particularly pertains to water tube boilers of the type having one or more elevated steam drums and one or more lower or water drums. The elevated steam drum or drums will normally be operated with the water level at the horizontal centerline of the drum or either slightly below or above it. When such a boiler is employed on shipboard, the water level may be partially rotated with respect to the horizontal centerline when the vessel is rolling or assume various angles to the longitudinal centerline of this drum. The tube bank or banks and the water drum or drums are normally filled either with water or mixture of water and steam.

Our invention resides in an improvement over previous methods of reducing turbulence, geysering, and entrainment of water in the steam drum as well as in reducing the amount of steam in the water flowing to the downcomer tubes passing from the steam drum to the water drum or drums of the boiler.

We are cognizant of the perforated, submerged baffle invented by H. G. Donald and disclosed in U. S. Patent No. 1,844,614, granted October 25, 1932, and of the multiple steam baffling invented by C. S. Gillette and R. C. Brierly, disclosed in U. S. Patent No. 2,283,201, granted May 19, 1942. These devices applicable to boilers operating at the steaming rates current at the time of their inception have proved in some instances of inadequate utility in boilers designed for the steaming rates and steam drum steam relieving areas presently obtaining. Whereas in the Donald patent mentioned, by far the major portion of the steam generated was evolved in the fireside tube rows, the outer tube rows acting as downcomers in the manner described in the specification thereof, and whereas in the Gillette-Brierly patent mentioned the tubes all spouted steam with circulating water supplied to these tubes by external connections or downcomers, present conditions have so multiplied the quantity of steam released by such tubes and so increased the force of geysering or impact that the screens mentioned in the specifications of the said applications in turn are approaching inadequacy for their intended purpose.

It is the object of our invention to reduce the carry-over of liquid with the steam in the same manner as described in the specifications for the Gillette-Brierly patent but simultaneously to reduce the force of geysering and of translation of water particles toward and into the dry pipe located at the top or near the top of the inner sur-

face of the steam drum. We accomplish this reduction in geysering force and translation toward the dry pipe by utilizing a solid baffle plate preferably concentric with the inner lower surface of the steam drum located a short distance above the exit ends of the boiler tubes. The purpose of this solid baffle is to provide an obstacle against which impact is largely expended and the path of steam-water mixture simultaneously altered. 5 If the steam generation in individual tube rows varies to such an extent that additional partitioning is desirable to distribute the mixture more equally to the two sides or ends of the steam drum, lateral baffles (either solid or perforated) parallel to the longitudinal axis of the steam drum may be located between the lower surface of the drum and the solid baffle plate mentioned; these longitudinal supplementary baffles parallel and generally radial to the longitudinal axis of the steam drum may also be utilized partly to strengthen the solid plate baffle structure. The sides (and, if necessary, the ends) of this concentric solid baffle are left open to provide space for the egress of the steam-water mixture which passes thence 10 upward to and through a perforated, submerged plate having apertures calculated by recognized mathematical principles to assure reasonable uniformity of distribution and/or dispersion of the mixture. The two principal plates, one solid, the other perforated, as described are normally to be employed in conjunction with the screen steam baffling described in the specifications of the Gillette-Brierly patent mentioned above, but may 15 be employed alone or in connection with other types of steam separators or devices for steam purification. The apertures of the upper plate or series of plates as required need not be circular, in fact, in some instances slots or V shaped distributing openings have proved equally or more 20 effective.

We are in no way concerned with reduction in carryover in steam which already left the surface of the liquid except in the possible instance where 25 water level is reduced to such an extent that the pressures of the screen baffling of our invention is in the steam filled section of the drum rather than below the water level. We are cognizant of many methods of reducing water in vapor after 30 its liberation from the surface of the liquid; these may be used in conjunction with our device with or without the screen baffling described in the 35 specifications for the aforementioned Gillette-Brierly patent but have no bearing upon them 40 except to improve their functioning by further

reduction of entrained moisture before the steam leaves the drum.

More effectively to reduce geysering and impact, the ends of the two baffles—preferably generally concentric to the lower inner surface of the steam drum—may be completely or partially closed or housed in, thus reducing tendencies toward bumping or surging of the steam-water mixture longitudinally toward the drum heads.

Inspection of tubes or their cleaning may require removal of all screen baffling and perforated or solid baffling from the steam drum. For this reason, we prefer an embodiment of our invention which will facilitate removal of all baffling from the steam drum. This may be accomplished by assembling each plate or screen in the form of panels which may be progressively and rapidly removed through the manhole or manholes of the drum or drums of the boiler.

The nature of our invention will become apparent from the final and detailed description when considered in connection with the accompanying drawings forming a part thereof and in which:

Figure 1 is a transverse, vertical sectional view, showing more or less diagrammatically, the steam generator embodying our invention;

Figure 2 is a transverse, vertical sectional view, on an enlarged scale, of the steam and water drum shown in Figure 1; and

Figure 3 is an isometric sectional view of portions of the dispersing baffle plates in which the present invention resides and which also have been shown in Figures 1 and 2.

Like characters of reference refer to the same or similar parts through the several views.

While we have shown our invention in the drawing in connection with an A type express boiler and utilized in conjunction with screen baffling of the general type disclosed in the Gillette-Brierly patent, it is to be specifically understood that we do not limit its use to this particular type of boiler or to application in conjunction with the previously patented or patent applied for screen baffles. The invention will attain equal efficiency when applied to any other type of water tube boiler where the tubes under the drum or drums submerge below the water level.

Referring to the drawings, reference character 10 designates the upper or steam and water drum of a steam generator embodying the invention, having spaced lower or water drums 11 and 12 which are connected to the drum 10 by banks of tubes 13 and 14, respectively. The furnace, not shown in the drawings, is located under and between the banks of tubes 13 and 14. The series of tubes close to the furnace are subjected to radiant as well as to convection heat while the tubes further out in the bank are normally subjected to progressively diminishing gas temperatures. Thus, the tubes adjacent to the furnace normally generate a greater quantity of steam than those located further outward in the tube banks. However, in present steam generators, all or nearly all of the tubes in the bank are generating tubes, especially at advanced firing rates. For these reasons, a solid curved plate 15 concentric with the drum has been shown covering the entire zone of tube ends, while superimposed above it is the aperture containing plate 16, having, as shown, its mid-portion curved to conform to the baffle 15 and its sides reversely curved and in contact with the inner wall of the drum. As previously stated, a number of aper-

tured plates 16 in superimposed and spaced relationship can be installed in this area as required.

As shown, one or more separating strips 17 parallel and generally radial to the longitudinal axis of the steam drum may be installed to separate and deflect the mixture from selected rows of tubes toward the sides or ends of the steam drum. Should installation of multiple separating strips similar to the one numbered 17 be indicated, the steam-water mixture can be caused to pass to the ends of the solid baffle plate. As shown in Fig. 2, the front and rear ends of the baffle plates below the baffle 16 are closed with end plates 18 of solid metal. The ends of the baffle plates between the plate 16 and the uppermost plate 19 are closed by perforated plates or screens 18'. The baffle plates 18 and 18' prevent surging or bumping of the steam-water mixture from the ends of the baffle plates.

The plates 15, 16, 17 and 18, in which the present invention primarily resides, are shown in conjunction with multiple screen baffling 19 and a special form of dry pipe 20 disclosed in a separate application for patent filed by us concurrently herewith, wherein, in one form, the dry pipe openings are moved as close as possible to the inner surface of the vapor drum, farthest from the water level without impeding steam flow to the apertures and without altering the form of the apertures, and in another form, the same result is obtained without change in the cross-section of the dry pipe but through an alteration residing entirely in the form of the aperture or apertures of the pipe. Although superior performance has been found possible through the use of plates, 16, 17 and 18 in conjunction with the screen baffle 19 and the special form of dry pipe 20, use of our invention is not confined, as previously stated, to boilers in which screen baffling and/or special forms of dry pipe are utilized. A number of types of steam-water separators or steam purifiers of which we are cognizant may be satisfactorily employed in conjunction with our invention.

It will be perceived from the foregoing that by the use of this invention the forces of impact and geysering of the steam-water mixture at the ends of the tubes will be so deflected and dispersed that relatively greater quiescence of mixture will exist above the upper, aperture containing, plate or plates and that greater uniformity of distribution or dispersion to such screen baffling or other separating devices as may be simultaneously employed will be increased. Moreover, in the steam and water mixture which passes to the external circulators or downcomers, there will be a reduction in steam content of the mixture, greater uniformity of distribution of the steam which may remain in the mixture and reduction in the particle size thereof, thus reducing tendencies toward steam pocketing in the circulation circuit of the boiler, simultaneously permitting higher rates of operation of the entire circuit to be obtained without carryover. The invention further minimizes moisture carryover when utilizing high water level or high contamination of feed water such as may exist in the form of sodium chloride, high alkalinity, or excessive total solids, as well as other impurities which may occur from evaporator or condenser leakage or other contamination sources—highly important considerations in boilers for marine use.

Inasmuch as changes and details of construction, proportion, and arrangement of parts which

may be consummated in the form of the invention disclosed without departing from the principles thereof, it will be understood that our invention is not to be limited except by the scope of the appended claims.

The invention herein described may be manufactured and used by or for the Government of the United States for government purposes without the payment of any royalty thereon.

What we claim is:

1. In a vapor generator having an elongated drum and vapor generating tubes having their discharge ends connected to the drum below the normal liquid level therein, an imperforate baffle extending longitudinally in the drum to a point short of one end of the drum, said baffle being spaced from the inner wall of the drum and from the discharge ends of some at least of the vapor generating tubes and disposed in the path of flow of the vapor and liquid mixture discharged from said tubes, said baffle being constructed and arranged to provide an outlet for the flow of vapor and liquid mixture from below the baffle, a perforated baffle extending longitudinally in the drum above the imperforate baffle and in spaced relationship thereto and in the path of flow of the vapor and liquid mixture flowing upwardly from below the imperforate baffle, both of said baffles being disposed below the normal liquid level in the drum, and an imperforate end plate extending transversely to the longitudinal axis of the drum at the end of the baffles adjacent said one end of the drum and extending between the perforate baffle and the inner wall of the drum.

2. In a vapor generator having an elongated drum and vapor generating tubes having their discharge ends connected to the drum below the normal liquid level therein, an imperforate baffle in the drum spaced from the discharge ends of some at least of the vapor generating tubes and disposed in the path of flow of the vapor and liquid mixture discharged from said tubes, said baffle being constructed and arranged to provide an outlet for the flow of vapor and liquid mixture from below the baffle, a perforated baffle above the imperforate baffle and in spaced relationship thereto and in the path of flow of the vapor and liquid mixture flowing upwardly from below the imperforate baffle, another perforated baffle spaced above the first mentioned perforated baffle and in the path of flow of the vapor and liquid flowing upwardly in the drum, each of said baffles extending longitudinally of the drum and below the normal liquid level therein to a point short of one end thereof, an imperforate end plate, and a perforated end plate, both of said end plates extending transversely of the longitudinal axis of the drum at the end of the baffles adjacent said one end of the drum, the imperforate end plate extending between the inner wall of the drum and the perforate baffle and the perforate end plate extending between the perforate baffle and said other perforate baffle.

3. In a vapor generator having an elongated drum and vapor generating tubes having their discharge ends connected to the drum below the normal liquid level therein, an imperforate baffle extending longitudinally in the drum to a point short of one end of the drum, said baffle being spaced from the inner wall of the drum and from the discharge ends of some at least of the vapor generating tubes and disposed in the path of flow of the vapor and liquid mixture discharged from said tubes, said baffle having a terminal portion

in spaced relationship with the inner wall of the drum, a perforated baffle extending longitudinally in the drum above the imperforate baffle and in spaced relationship thereto and in the path of flow of the vapor and liquid mixture flowing upwardly from below the imperforate baffle, both of said baffles being disposed below the normal liquid level in the drum, and an imperforate end plate extending transversely to the longitudinal axis of the drum at the end of the baffles adjacent said one end of the drum and extending between the perforate baffle and the inner wall of the drum.

4. In a vapor generator having an elongated drum and vapor generating tubes having their discharge ends connected to the drum below the normal liquid level therein, an imperforate baffle extending longitudinally in the drum to points short of the opposite ends of the drum, said baffle being spaced from the inner wall of the drum and from the discharge ends of some at least of the vapor generating tubes and disposed in the path of flow of the vapor and liquid mixture discharged from said tubes, said baffle being constructed and arranged to provide an outlet for the flow of vapor and liquid mixture from below the baffle, a perforated baffle extending longitudinally in the drum above the imperforate baffle and in spaced relationship thereto and in the path of flow of the vapor and liquid mixture flowing upwardly from below the imperforate baffle, both of said baffles being disposed below the normal liquid level in the drum, and imperforate end plates extending transversely to the longitudinal axis of the drum at the ends of the baffles adjacent said opposite ends of the drum and extending between the perforate baffle and the inner wall of the drum.

5. In a vapor generator having an elongated drum and vapor generating tubes having their discharge ends connected to the drum below the normal liquid level therein, an imperforate baffle extending longitudinally in the drum to a point short of one end of the drum, said baffle being spaced from the inner wall of the drum and from the discharge ends of some at least of the vapor generating tubes and disposed in the path of flow of the vapor and liquid mixture discharged from said tubes, said baffle being constructed and arranged to provide an outlet for the flow of vapor and liquid mixture from below the baffle, a perforated baffle extending longitudinally in the drum above the imperforate baffle and in spaced relationship thereto and in the path of flow of the vapor and liquid mixture flowing upwardly from below the imperforate baffle, both of said baffles being disposed below the normal liquid level in the drum, the perforations in said perforated baffle being arranged therein so as to assure equality of distribution of vapor particles in the mixture of vapor and liquid above said perforated baffle, and imperforate end plates extending transversely to the longitudinal axis of the drum at the ends of the baffles adjacent said opposite ends of the drum and extending between the perforate baffle and the inner wall of the drum.

6. In a vapor generator having a cylindrically shaped, substantially horizontally extending drum and vapor generating tubes having their discharge ends connected to the drum below the normal liquid level therein, a substantially semi-circular shaped imperforate baffle extending longitudinally in the drum to points short of the opposite ends of the drum and conforming to the configuration of the inner wall of the drum and

spaced from the discharge ends of some at least of the vapor generating tubes and disposed in the path of flow of the vapor and liquid mixture discharged from said tubes, said baffle having terminal portions below the normal liquid level in the drum, a perforated baffle above the imperforate baffle and in spaced relationship thereto, said perforated baffle being of substantially the same configuration as the imperforate baffle but extending over and in spaced relationship to the terminal portions of said imperforate baffle and into contact with the inner wall of the drum, the perforate baffle being disposed in the path of flow of the vapor and liquid mixture flowing upwardly from below the imperforate baffle, both of said baffles being disposed below the normal liquid level in the drum, and imperforate end plates extending transversely to the longitudinal axis of the drum at the ends of the baffles adjacent said one end of the drum and extending between the perforate baffle and the inner wall of the drum.

7. In a vapor generator having an elongated drum and vapor generating tubes having their discharge ends connected to the drum below the normal liquid level therein, an imperforate baffle in the drum spaced from the discharge ends of some at least of the vapor generating tubes and disposed in the path of flow of the vapor and liquid mixture discharged from said tubes, said baffle being constructed and arranged to provide an outlet for the flow of vapor and liquid mixture from below the baffle, a perforated baffle above the imperforate baffle and in spaced relationship thereto and in the path of flow of the vapor and liquid mixture flowing upwardly from below the imperforate baffle, another perforated baffle spaced above the first mentioned perforated baffle and in the path of flow of the vapor and liquid flowing upwardly in the drum, each of said baffles extending longitudinally of the drum and below the normal liquid level therein to points short of the opposite ends thereof, imperforate end plates, and perforated end plates, said end plates extending transversely of the longitudinal axis of the drum at the opposite ends of the baffles adja-

cent said opposite ends of the drum, the imperforate end plates extending between the inner wall of the drum and the perforate baffle and the perforate end plates extending between the perforate baffle and said other perforate baffle.

8. In a vapor generator having a cylindrically shaped substantially horizontally extending drum and longitudinally extending rows of vapor generating tubes having their discharge ends connected to the drum below the normal liquid level therein, a substantially semi-circular shaped imperforate baffle extending longitudinally in the drum to points short of the opposite ends of the drum and conforming to the configuration of the inner wall of the drum and spaced from the discharge ends of some at least of the vapor generating tubes and disposed in the path of flow of the vapor and liquid mixture discharged from said tubes, said baffle having terminal portions below the normal liquid level in the drum, a longitudinally extending baffle disposed between the imperforate baffle and the inner wall of the drum and separating the discharge ends of one row of tubes from the discharge ends of another row of vapor generating tubes and one of the terminal portions of the imperforate baffle, a perforated baffle above the imperforate baffle and in spaced relationship thereto, said perforated baffle being of substantially the same configuration as the imperforate baffle but extending over and in spaced relationship to the terminal portions of said imperforate baffle and into contact with the inner wall of the drum, the perforate baffle being disposed in the path of flow of the vapor and liquid mixture flowing upwardly from below the imperforate baffle, said perforate and imperforate baffles being disposed below the normal liquid level in the drum, and end plates extending transversely to the longitudinal axis of the drum at the ends of the baffles adjacent said opposite ends of the drum and extending between the perforate baffle and the inner wall of the drum.
